CURTAIN STRETCHER

Fredrick Sievern and John F. Lizak,
McKeesport, Pa.

Application February 28, 1934, Serial No. 713,342

8 Claims. (Cl. 45—24)

Our invention relates to stretchers for supporting curtains and the like, and holding them in a taut condition while drying.

One object of our invention is to provide a stretcher having improved fastening devices on the stretcher bars, to which the edges of the curtains can be progressively connected, and wherein in the use of sharp brads or pins for holding the curtain is rendered unnecessary.

10 Another object of our invention is to provide progressively-arranged fastening devices for the edges of the curtains, which are adjustable in directions parallel to the edges of the curtains.

Still another object of our invention is to provide 15 fastening devices of the screw-clamping type, so arranged that certain of said fastening devices at each edge can be employed for first fastening one curtain in place, and others of said fastening devices can be utilized to fasten an additional curtain in place on top of the first curtain, without disturbing the first-named fastening devices.

Some of the forms which our invention may take are shown in the accompanying drawing 25 wherein Figure 1 is a face view of the stretcher; Fig. 2 is an end view thereof; Fig. 3 is an enlarged view, taken on the line III—III of Fig. 1; Fig. 4 is an enlarged view taken on the line IV—IV of Fig. 1; Fig. 5 is a fragmentary face 30 view showing one manner in which the clamping devices may be employed for holding a plurality of curtains in place; Fig. 6 is a sectional view thereof, and Fig. 7 is a cross-sectional view showing a modified screw-clamping device.

35 The bars constituting the stretcher frame may be assembled and adjusted in somewhat the usual manner. In the drawing, we have indicated longitudinal or edge bars by the numerals 8 and 9, the transverse or end bars by the numerals 10 and 11, and the legs by the numeral 12. The longitudinal and the end bars are adjustably connected together by clamps 13, 14, 15 and 16, in a manner well-known in the art.

40 The stretcher bars 8, 9, 10 and 11 are grooved for the reception of metal channels 17 which are fastened in place by suitable screws 18, and have their outer edges inturned, as shown more clearly in Figs. 3 and 4.

45 The channels serve as slideways for the heads of screws 19, a suitable number of which are placed in each channel. The channels 17 are bent upwardly at their outer ends as indicated at 21, to keep the screws from sliding out and becoming lost. A clamping nut or button 22 has 50 threaded engagement with each of the screws 19,

and is utilized to clamp the edges of the curtains against the outer faces of the channels 17, thus avoiding the use of the pins which are commonly employed, and which are objectionable for various reasons, such as because they prick the fingers of the user and are more likely to cause tearing of the curtains. The heads of the screws are squared to prevent rotation thereof in the channels when the buttons are being turned.

55 In using the structure, the frame is assembled in the manner shown in Figs. 1 and 2, for example, in accordance with the size of curtains to be stretched. A suitable number of clamping screws, with their buttons 22, are positioned within the rectangular area of the frame, the surplus buttons and screws being stored at the free ends of the stretcher bars. The buttons can, of course, be spaced apart any suitable distance, and such adjustment is particularly convenient when curtains having scalloped edges are to be stretched.

60 In placing a curtain in position on the stretcher frame, the operator may first fasten the curtain at one corner of the frame by turning the button down to clamp one corner of the curtain. The curtain may then be stretched along its edges, and progressively clamped by the other buttons. It will be understood that either a single curtain or a plurality of curtains can thus be fastened in place.

65 Referring to Figs. 5 and 6, we show an arrangement whereby a single curtain 24 may first be fastened in place and a second curtain 25 then fastened in place, without disturbing the buttons which hold the curtain 24. In such instances, a greater number of clamping buttons will be employed than as shown in Fig. 1. Alternate buttons 22a will be utilized to hold the curtain 24, whereupon the curtain 25 can be brought into position beneath the buttons 22b and clamped thereby.

70 The buttons 22a will not interfere with the placing of the curtain 25, because the edges of the curtain can lie within the annular grooves 26 which are formed in the buttons. The channels 17, screws 19, and buttons 22, will preferably be made of material which will not readily corrode. It will be understood that undercut grooves for the heads of the screws 19 could be cut directly in the bars without the necessity of employing the metal channels 17, but we prefer to employ the metal channels 17 because they serve to reinforce the frame bars and prevent sagging thereof.

75 The buttons 22, in addition to clamping the

edges of the curtain to the channel strips 17, also cause the heads of the screws 19 to be clamped in place in the strips, and thereby held against slipping.

5 In Fig. 7, we provide button-head screws 30 that have screw-threaded engagement with nuts 31 that are disposed within a channel 32 of a frame bar 33. The screws extend through the nuts 31 and at their inner ends are peened over 10 or have their end threads mutilated to prevent the screws being disengaged from the nuts 31, and consequently, the screws and buttons cannot be lost accidentally during handling of the curtain stretcher bars. In order to accommodate 15 the ends of the screws 30, the base of the channel 32 is depressed to provide a longitudinally-extending groove therein.

We claim as our invention:—

- 20 1. A curtain stretcher comprising side bars and end bars, having slideways formed therein, screws slidably supported in said slideways, and clamping buttons carried by said screws in position to effect clamping engagement with the edges of a curtain.
- 25 2. A curtain stretcher comprising side bars and end bars, having undercut slideways formed therein, screws having their heads supported in the said slideways and protruding at the faces of the said bars, and curtain-clamping buttons carried by said screws.
- 30 3. A curtain stretcher having bars provided with slots, channel strips positioned in said slots and having their edges inturned at the faces of the bars, screws having their heads slidably positioned in said strips, and clamping buttons having threaded engagement with the outer ends of the screws.

4. A curtain stretcher having a plurality of rows of curtain-clamping buttons, certain of the buttons in each row having peripheral grooves in which the edges of a curtain may lie when the curtain is clamped by the other buttons. 5

5. A curtain stretcher comprising bars having undercut slideways formed therein, screws having their heads supported in said slideways and protruding at the faces of the bars, and clamping buttons having threaded engagement with the outer ends of the screws, and positioned to clamp curtains against the bars, and to draw the heads of the screws into clamping engagement with the undercut portions of the slideways. 10

6. A stretcher frame having undercut slide- 15 ways formed therein, nuts disposed in said slide- ways, headed curtain-clamping screws having their inner ends extending through said nuts, and means for limiting outward movement of the screws relative to the nuts. 20

7. A stretcher frame having undercut slide- 25 ways formed therein, nuts disposed in said slide- ways, headed curtain-clamping screws having their inner ends extending through said nuts, and means for limiting outward movement of the screws relative to the nuts, the bottom wall of the slideway having a narrow recess for receiving the innermost ends of the screws. 30

8. A stretcher frame having undercut recesses formed therein for the reception of nuts, and headed curtain-clamping screws having their inner ends extending into said nuts.

FREDRICK SIEVERN.

JOHN F. LIZAK.
